STEADY BEARING FOR CENTRIFUGAL
SEPARATORS

John F. Tholl, Needham, Mass., assignor to American Tool and Machine Company, Hyde Park, Mass., a corporation of Massachusetts

Application August 30, 1932, Serial No. 631,074

5 Claims. (Cl. 308—142)

This invention relates to centrifugal separators and is more especially concerned with centrifugals of the suspended type.

Such machines are much used in the sugar industry and in other lines, especially in connection with extracting, washing and refining operations. In using these machines it is a common practice to unload or discharge the material collected on the inside of the revolving basket by means of a 10 scraper which is forced laterally into the wall of solid material and is then traversed in a direction parallel to the lining of the basket, this movement cooperating with the rotary motion of the basket to dislodge the accumulated solids and to 15 cause them to drop through the bottom of the basket. The flexible mounting or support for suspended centrifugals introduces difficulties in performing the discharging operation in this manner, particularly when the material to be 20 unloaded is packed fairly hard, because the laterally directed pressure of the scraper in entering this wall of material deflects the revolving basket, thus causing unusual strain on the entire mechanism and tending to produce violent vibratory 25 movements of the basket.

The present invention deals especially with these conditions and it aims to devise a thoroughly practical solution for them.

The nature of the invention will be readily 30 understood from the following description when read in connection with the accompanying drawings, and the novel features will be particularly pointed out in the appended claims.

In the drawings, 35 Figure 1 is a vertical, sectional view of a suspended centrifugal constructed in accordance with this invention;

Figs. 2 and 3 are side views illustrating, on a larger scale, certain details of the construction 40 shown in Fig. 1, some of the parts in Fig. 2 being shown in section; and

Fig. 4 is a view similar to Fig. 2 illustrating a modification.

Fig. 1 shows the invention as applied to the 45 machine known commercially as the Weston centrifugal which has been on the market for many years. This machine includes a basket 2 mounted to rotate in the usual curb or casing 3, the basket being suspended from overhead by means of an 50 inside spindle 4 which is hung on a ball 5 mounted in the supporting bracket 6. The usual spider at the bottom of the basket is bolted to the lower end of an outside spindle 7 carrying a pulley 8 at its upper end by means of which the spindle may 55 be belted to any convenient source of power.

The weight of the basket and its load is transmitted to the inside spindle through a step bearing 10 of an anti-friction type, and the lower end of this bearing is enclosed in a cup 12 which is bolted to the outside spindle and which holds a 5 quantity of oil or other lubricant in contact with the bearing.

All of these parts are constructed, arranged and operated in the usual manner except that the usual cup at the bottom of the step bearing has 10 been replaced by a special cup, best shown in Fig. 2, which is provided with a short downwardly extending shaft 13 co-axial with the spindles 4 and 7. This shaft revolves in a bearing bushing 14 carried by a collar 15 to which one end of a laterally extending arm 16 is secured. The opposite end of this arm extends through and is free to slide in a bracket 17 which is secured rigidly to the curb or casing 3 of the machine, as will be evident from an inspection of Figs. 1 and 3. An 20 upright rod 18 having a handle 20 secured to its upper end is threaded through the bracket in such a manner that its lower end can be made to bear on the flattened end of the rod 16 to clamp 25 this rod securely to the machine frame or casing. Preferably the arrangement is such that only a partial rotation of the rod 18 is required to clamp or release the arm 16.

With this arrangement the machine may be 30 operated in the usual manner and with no change whatever in results until the unloading or discharging operation is begun, the rod 18 being slightly raised so as to leave the arm 16 free during all of this time. Consequently, the bearing for the shaft 13 is free to swing or to gyrate 35 in a horizontal plane and will follow any gyroscopic or swaying movements of the axis around which the basket revolves. Immediately prior to performing the discharging operation, however, the handle 20 is turned to clamp the rod 16 to 40 the stationary bracket 17. Usually the basket is running smoothly at this time so that this clamping movement simply locks the lower bearing 15 in position to steady the spindle 7 and the basket while they continue to revolve normally. When 45 the scraper or discharger is pressed laterally against the wall of solid material accumulated on the lining of the basket, it is entered in this material more easily because of the fact that the lower end of the spindle 7 is steadied by the 50 supplemental bearing mechanism located below the basket. At the same time this mechanism also prevents any substantial deflection of the spindle due to the lateral thrust of the discharger or unloader, and therefore prevents the 55

undesirable vibration which frequently attends this step in the unloading operation and which also is accompanied by increased strain on the entire supporting and driving mechanism. Consequently, the unloading operation is performed more easily and smoothly and danger of injuring the lining of the basket is minimized. Preferably the scraper should be brought into contact with the accumulated solids by a movement 5 in a direction parallel to the rod 16 to enable this rod and the bearing mechanism better to take the lateral thrust exerted by the scraper. After the unloading operation has been completed the handle 20 is given a partial turn to raise the rod 18 and thus release the arm 16. When so released the lower bearing is entirely free to move with the axis of rotation of the basket so that the machine will operate exactly as though the mechanism provided by this invention were not present. Furthermore, the 10 change into either a locked or released condition can be produced instantly and without interfering in any way with the normal operation of the machine.

25 In some cases it is found desirable to provide means for cushioning vibrations of the shaft 13 when the arm 16 is locked in its relatively stationary position. This may conveniently be done by interposing a rubber bushing or rubber segments 30 between the bearing bushing 14 and the collar 16. Such a construction is illustrated in Fig. 4 in which the collar 15' is like the collar 15 except that it is made somewhat larger and it is counter-bored to receive a rubber bushing 35 21 which encircles the bearing bushing 14. The rubber bushing is held against any substantial vertical displacement by means of an inwardly projecting upper flange on a collar 15' and an outwardly projecting lower flange on the bearing bushing 14.

40 It will now be appreciated that this invention provides an exceedingly simple, reliable, and easily operated arrangement for steadyng the basket during the unloading operation. At the same time the arrangement is such that the basket 45 is free to find its own axis of rotation when running in a normal manner.

50 While I have herein shown and described a preferred embodiment of my invention, it will be evident that the invention may be embodied in other forms without departing from the spirit or scope thereof.

Having thus described my invention, what I desire to claim as new is:

55 1. In a centrifugal separator, the combination with a basket and means supported at a point above the basket for suspending the basket for rapid rotation about an approximately vertical axis, of a shaft extending downwardly from said

basket, a bearing for said shaft located below said basket and mounted to swing in a horizontal plane with said shaft, an arm connected with said bearing and extending laterally therefrom, a stationary guide into which said arm projects, and means for clamping said arm to said guide. 5

2. In a centrifugal separator, the combination with a basket and means supported at a point above the basket for suspending the basket for rapid rotation about an approximately vertical axis, of a shaft extending downwardly from said basket, a bearing for said shaft located below said basket and mounted to swing in a horizontal plane with said shaft, an arm connected with 10 said bearing and extending laterally therefrom toward the frame of the machine, a bracket secured to said frame and having a guideway in which said arm slides, and a rod threaded through said bracket to bear on said arm for 15 clamping it to the bracket.

3. In a centrifugal separator, the combination with a basket and means for suspending the basket for rapid rotation about an approximately vertical axis, of a shaft extending downwardly 20 from said basket, a bearing for said shaft located below said basket and mounted to swing normally in a horizontal plane with said shaft, means associated with said bearing for cushioning said swinging movement, and means operable at the will of the attendant for locking said bearing in position to control said swinging movement without disturbing said cushioning action. 25

4. In a centrifugal separator of the type in which the basket is suspended for rapid rotation 30 about an approximately vertical axis, the combination of a shaft extending downwardly from said basket, a bearing for said shaft located below said basket and mounted to swing in a horizontal plane with said shaft, an arm connected 35 with said bearing and extending laterally therefrom, and means for locking said arm in position to steady said bearing, said means being 40 instantly releasable to unlock the arm.

5. In a centrifugal separator of the type in which the basket is suspended for rapid rotation about an approximately vertical axis, the combination of a shaft extending downwardly from said basket, a bearing for said shaft located below said basket and mounted to swing in a horizontal plane with said shaft, an arm connected with said bearing and extending laterally therefrom, and means for locking said arm in position to steady said bearing, said means including a single control element operable to lock or release the arm instantly while the machine continues in operation. 45 50 55
